GUIDE FOR GOLF PUTTER

George Hunt Weber, 1 Royal Palm Way,
Palm Beach, Fla. 33480

Filed Sept. 21, 1973, Ser. No. 400,311

Term of patent 14 years

Int. Cl. D21—02

U.S. Cl. D34—5 CB

FIG. 1

FIG. 2

FIG. 3

FIG. 4

FIG. 5

FIG. 6

FIG. 7

FIG. 1 is a perspective view of a guide for golf putter showing my new design;

FIG. 2 is a plan view thereof;

FIG. 3 is a side elevation thereof;

FIG. 4 is an end elevation looking from the left end of FIG. 2;

FIG. 5 is an end elevation looking from the right end of FIG. 2;

FIG. 6 is a bottom plan view of the invention; and

FIG. 7 is a vertical section on line 7—7 of FIG. 1.

I claim:

The ornamental design for a guide for golf putter, as shown.
